MARQUIS H. LOCKWOOD, OF NEW YORK, N. Y., ASSIGNOR TO UNDERWOOD TYPEWRITER COMPANY, OF NEW YORK, N. Y., A CORPORATION OF DELAWARE.

TYPE-WRITER RIBBON-CARRIER.

1,027,488.

Specification of Letters Patent. Patented May 28, 1912.

Application filed December 1, 1911. Serial No. 663,307.

To all whom it may concern:

Be it known that I, MARQUIS H. Lockwood, a citizen of the United States, and resident of the borough of Manhattan, city, 5 county, and State of New York, have invented certain new and useful Improvements in Type-Writer Ribbon-Carriers, of which the following is a specification.

My invention relates more particularly to a ribbon carrier which is vibrated to cause the ribbon to cover and uncover the printing point when the keys of the type- 10 writer are operated in the usual manner.

The ribbon carrier shown and described 15 herein is adapted for use in the well known Underwood typewriter but it will be readily understood that my improvements may be adapted for use in other front-strike visible writing machines. In machines of 20 this character a narrow ribbon is used, which of necessity must be replaced more or less frequently and more particularly if a two colored ribbon is used. It is also frequently desirable to write one class of 25 work with one color or kind of ink or inks and another class with an entirely different color or kind of ink in which case the spools and ribbon of one kind are removed and the other substituted therefor. With the ordinary carrier the operator has considerable 30 difficulty in effecting this replacement or exchange of the ribbon owing to the manipulation required in removing and properly replacing the ribbon in the guide slots or 35 eyes of the carrier, and usually results in soiled fingers. My improved ribbon carrier is intended to obviate these difficulties and render it possible to readily remove or 40 replace the ribbon without soiling the fingers. To this end my ribbon carrier is bifurcated, in the usual manner, at the upper end to form two rigid arms with a space between them for the type to strike 45 the ribbon against the paper on the platen; and a pair of movable arms is mounted adjacent to the respective rigid arms so as to form, in conjunction therewith, a pair of 50 guide eyes for the ribbon. The movable arms are under suitable spring tension, at 55 their lower ends, acting in such manner that their upper or free ends tend to move in opposite directions until they stand at an angle to their respective rigid arms, thus opening the guide eyes for the convenient removal or insertion of the ribbon. The upper ends of the rigid arms, above referred

to, are provided with ears which are bent forward and inward to form hooks into which the upper ends of the movable arms may be seated and thus close the guide eyes 60 so as to retain the ribbon in place as the ribbon carrier is vibrated.

One form of my invention is illustrated in the accompanying drawings of which—

Figure 1 is a front elevation of the carrier with the guide eyes closed. Fig. 2 is a similar view representing the guide eyes open as for the removal or insertion of the ribbon. Fig. 3 is a side view of Fig. 2.

The ribbon carrier A is shown separate 70 from the typewriter but its use and mode of operation are fully understood by those familiar with the art and with the well known Underwood typewriter.

B represents the lower end of the carrier 75 which is adapted to be connected with the usual vibrating lever so that in use the ribbon is vibrated to cover and uncover the printing point as the typewriter is operated. The upper end of the carrier is bifurcated to form integral rigid arms C, C, 80 spaced apart sufficiently to permit the type to strike between them.

D represents the usual ears adapted to hold the carrier in place on its slide as in 85 the regular construction of the Underwood machine.

In carrying out my improvement I provide each of the rigid arms C with a laterally extending ear E, near the lower ends 90 thereof adapted to locate the lower edge of the ribbon. The outer end of the ear E is bent or rolled forward and inward at E' to form a securing means for the spring F, the coil of which preferably surrounds E' 95 and has one end F' bent inward, radially of the coil, and secured in the rolled end E' of the ear E. The other end of the wire forming the spring F is bent upward to serve as the movable arm which, in conjunction with one of the rigid arms C, 100 forms a guiding eye for the ribbon and is adapted, under the action of its spring F, to stand at an angle to the respective rigid arm C as indicated in Figs. 2 and 3 of the drawings. The upper end of the arm G is 105 formed into a loop G' to give it a finished appearance, and is adapted to facilitate the manipulation of the arms G as hereinafter described. The upper ends of the rigid arms C are provided with laterally extending ears H, each of which is bent forward 110

and then inward to form a hook H' adapted to receive the upper end of the respective movable arm G and retain it against the action of its spring in a position substantially parallel to the adjacent rigid arm C and thus form the guiding eyes for retaining the ribbon K while being vibrated to cover and uncover the printing point in the usual manner.

10 The operation of the device is extremely simple and should be readily understood from the drawings. With the ribbon in place the movable arms G will rest in the hooks H' as shown in Fig. 1. If it is desired to remove the ribbon the upper ends G' of the arms are pressed toward each other by the finger and thumb and pulled slightly forward until free of the hooks H' and then released, when they will move, 15 under the action of the springs F, to the position indicated in Fig. 2. With the movable arms G in this position (Figs. 2 and 3) the ribbon may be readily lifted out. Another ribbon may be inserted, as desired, 20 by placing the ribbon in the open arms of the carrier as shown in Fig. 2; the arms G are then pinched together or pressed inward and slightly rearward and upon being released are allowed to seat themselves in the 25 hooks H' thus closing the guide eyes over the ribbon and restoring the parts to the condition shown in Fig. 1.

Various modifications in the construction and arrangement of parts may be made 30 without departing from the spirit and scope of my invention, as set forth in the appended claims.

I claim:

1. In a typewriting machine the combination of a ribbon carrier provided with a pair of rigid arms, a pair of movable arms adapted, in conjunction with said rigid arms, to form guiding eyes for the ribbon, springs connected to and acting to urge said movable 45 arms in opposite directions and means for maintaining the movable arms, against the action of said springs, adjacent to the respective rigid arms to form said guiding eyes.

50 2. In a typewriting machine the combination of a ribbon carrier, bifurcated to form a pair of rigid arms, a pair of movable arms adapted, in conjunction with said rigid arms, to form guiding eyes for the ribbon, springs integrally connected to and acting to urge said movable arms in opposite directions until each assumes a position at an angle to its respective rigid arm, and means for maintaining the movable arms, against 55 the action of said springs, adjacent to the respective rigid arms to form said guiding eyes.

60 3. In a typewriting machine the combina-

tion of a ribbon carrier bifurcated to form a pair of rigid arms, ears extending laterally from the lower ends of said rigid arms to position the lower edge of the ribbon, a pair of movable arms connected to said ears and adapted in conjunction with said rigid arms to position the lower edge of the ribbon, a 70 springs connected to the lower ends of said movable arms and acting to urge the upper ends thereof in opposite directions until each assumes a position at an angle to its respective rigid arm, and means for maintaining the movable arms, against the action of said springs, adjacent to the respective rigid arms to form said guiding eyes.

4. In a typewriting machine the combination of a ribbon carrier bifurcated to form a 80 pair of rigid arms, ears extending laterally from the lower ends of said rigid arms to position the lower edge of the ribbon, a pair of movable arms connected to said ears and adapted in conjunction with said rigid arms, to form guiding eyes for the ribbon, 85 springs, integral with the lower ends of said movable arms and acting to urge the upper ends thereof in opposite directions until each arm assumes a position at an 90 angle to its respective rigid arm, means for securing the ends of the respective springs to said lateral ears and thus connect said movable arms thereto and means for maintaining the movable arms, against the action 95 of said springs adjacent to the respective rigid arms to form said guiding eyes.

5. In a typewriting machine the combination of a ribbon carrier bifurcated to form a pair of rigid arms, ears extending laterally from the lower ends of said rigid arms to position the lower edge of the ribbon, a pair of movable arms connected to said ears and adapted in conjunction with said rigid arms, to form guiding eyes for the ribbon, 105 springs, integral with the lower ends of said movable arms and acting to urge the upper ends thereof in opposite directions until each arm assumes a position at an angle to its respective rigid arm, means for securing the ends of the respective springs to said lower lateral ears and ears extending laterally from the upper ends of said rigid arms, bent forwardly and inwardly to form hooks 110 for maintaining the movable arms, against 115 the action of said springs, adjacent to the respective rigid arms to form said guiding eyes.

In testimony whereof, I have hereunto set my hand in the presence of two subscribing 100 witnesses.

MARQUIS H. LOCKWOOD.
